UNITED STATES PATENT OFFICE.

RUDOLF HEINRICH WIEGERT, OF MAGDEBURG, GERMANY.

METHOD OF AND MEANS FOR GAS-TIGHT SEALING OF SHAFTS.

Application filed May 22, 1928, Serial No. 111,080, and in Sweden, April 8, 1924.

In machines operating with injurious gases which are gas-tightly enclosed, as, for instance, gas compressors, the use of stuffing boxes for tight inlet of the driving draft is 5 non-economical and difficult due to their power-consuming action and troublesome attendance. Such a stuffing box, when used, for instance, in a plant of small capacity, may consume up to 100% of the theoretic 10 need of power and is, moreover, very difficult to keep tight, apart from the renewal of the packing material which, as in cooling machines, always requires special knowledge. Attempts have been made to hermetically 15 seal machines and have resulted in expensive electrical machines in which the movement of compression is obtained, for instance, by the provision of a short-circuit rotor enclosed inside a cap-shaped portion of the 20 hermetically sealed machinery and operated through the wall of said cap by a stator surrounding said cap. In such case very high losses are caused due to the production of eddy currents in the wall of the cap and due 25 also to a lowering of the power factor as well as of the efficiency as a result of the increase of the distance between the rotor and the stator (that is the air-gap). In addition, such an arrangement may only be used 30 for direct electric drive by means of alternating current.

Certain other designs of machines comprising hermetically sealed receptacles are restricted to apparatus operating on a cycle (as 35 cooling machines). In such machines the compressor enclosed within one of the sealed, rotary receptacles, is driven by a counter-weight, and the condenser as well as the generator rotates with its outside in contact 40 with cooling water or sea-water, whereby high friction losses are caused.

An object of the present invention is to overcome the said difficulties inherent to well-known driving systems for gas-tightly 45 enclosed machines.

Another object of the invention is to reduce the losses of the driving system as far as possible.

A still further object is to permit the use 50 of any type of driving motor and any driving fluid desired without intermediate means.

These and other objects will be obtained by balancing the pressure existing within the

chamber, apparatus, or the like to be kept 55 tight, from outside by providing a receptacle around the shaft as it projects from the said chamber and filling said receptacle with a pressure medium the pressure of which is caused to always correspond to the pressure existing in the chamber or the like to be kept 60 tight thereby preventing leakage from or to the said chamber.

The nature of the invention will be best understood from the following detailed description of its operation taken in connection with 65 the accompanying drawing in which:

Fig. 1 is a longitudinal section of one embodiment of the invention as applied to a cooling machine.

Fig. 2 is a longitudinal section of a modified embodiment with certain parts removed.

Fig. 1 shows a cooling machine comprising a compressor 4 adapted, when in operation, to draw a gaseous fluid by suction from the chamber 20 and deliver it into the chamber 3 where said compressor is housed. The driving shaft 2 of said compressor projects through the wall of the chamber 3 and extends outside said wall through a chamber 1. Said chamber 1 contains oil to a level above 80 the shaft 2 and its bearings. The space above the oil level in the chamber 1 communicates with the chamber 3 through an oil overflow pipe 21 terminating below the level of the shaft within the chamber 3.

Situated at the opposite side of the chamber 1 to the chamber 3 is a balancing receptacle 5 filled with oil, said receptacle surrounding the shaft 2, and outside said receptacle 5 the shaft 2 extends through an additional receptacle 6 normally filled with oil to a certain level.

When the machinery is in operation, a small pump 7 housed in the receptacle 6 will pass oil through a pipe 8 from the receptacle 6 into the receptacle 5 to maintain in the latter a pressure equal to that existing in the chamber 1. Due to the fact that the pressures within 1 and 5 are equal, no leakage can take place from 1 to 5 or vice versa. The 95 tight sealing between 1 and 5 may be made still more effective by using a long bearing which may be hardened and ground, if desired, and by hardening and grinding the corresponding portion of the shaft. Furthermore, it is of advantage to have the 100

shaft with its bearings within the chamber 1 immersed in the oil. The higher specific gravity of the oil as well as its viscosity will insure a better sealing effect than what may be obtained by the use of gas contact at the shaft. The viscosity of the oil may be further increased by water cooling. In operation, a completely tight sealing may be obtained at the inlet of the shaft by the system above described. The point of leakage is, so to say, moved one step outwardly from the receptacle to be kept tight, that is, to the entrance of the shaft from chamber 5 to chamber 6. By using a long and carefully worked bearing the leakage may be reduced at this point to an amount that may be readily balanced by the capacity of the small pump 7. The capacity of the pump 7 may, preferably, be about twice as large as the leakage.

Due to the fact that all stuffing box friction is avoided and the pressure balancing medium consists of oil that will cause a reduction of the frictional losses in the bearings to the lowest amount possible (the oil pressure will balance the shaft so as to lift it from the bearing between the chambers 5 and 6) an ideal mechanical efficiency may be obtained by the system described. The loss of work in the pump 7, whose piston diameter may be something about 5-8 mm., is negligible.

It may appear that if the pressure on the shaft 2 is the same in all directions, said shaft cannot be lifted from its bearings. However, the pressure on the shaft 2 is the same only at the bearing between 9 and 5, while in the chamber 5 a different pressure prevails, for instance, 3 to 6 atm., prevails in the chamber 5, which is different from the atmospheric pressure that prevails in the room 6. Because of the pressure difference between rooms 5 and 6 the oil will be pressed around the shaft 2 outwardly from 5 to 6. This oil current holds the shaft 2 out of contact with the bearing metal, in practice, the bearing between 5 and 6 is considerably longer than that between 9 and 5 and consequently the former bearing has the greater influence on the journaling of the shaft. Because of the friction in the bearing between 5 and 6 being considerably reduced, an ideal mechanical efficiency is obtained. Experiments have shown that the machine has an efficiency of 25 per cent greater than that of a machine provided with solid packing material.

With the machinery at rest the pump 7 will no longer balance the pressure within the receptacle 5. Now, the advantage of mounting the shaft frictionless, that is, without stuffing box and free from any hindrance against a smaller axial displacement thereof, will appear. Due to the difference in pressure existing between the main receptacle 1

and the atmosphere into which the shaft 2 projects, said shaft will be pressed with the power

$$P = \frac{d^2}{4}$$

70

against the hardened, and carefully ground end surface of the bearing, as at 9, and will thus act as a nonreturn valve. This requires the provision of a movable clutch, as 10, between the driving shaft 2 to be sealed and the shaft of the compressor and, if desired, also between the driving engine, not shown, and said driving shaft 2.

It is a characterizing feature of the present invention that the shaft 2 or a part thereof is movable against the seat at 9 and hence when the flange 9 is stationary with respect to the shaft 2, the shaft 2 must be movable not only at the clutch 10 between the shaft 2 and the compressor shaft but also between the said shaft 2 and the clutch of a driving motor. The shaft 2 in practice is partially fixed and movably connected with the flange 9 as for instance by means of a movable sleeve.

With the invention applied to electrically driven compressors or the like a hand-wheel 11 may be connected to the electrical contact and to the cooling water cock or valve in such a way as to enable control of the machine with all its auxiliary devices by a single manipulation. The hand-wheel 11 is also for the purpose of insuring the above said action of the shaft as a valve, inasmuch as it will cause a longitudinal displacement of the shaft when rotated. The system may then be operated as a usual stop valve in which case the shaft may be considered to constitute the valve stem. In starting the machine the hand wheel 11 is operated to release the pressure against 9 exerted by the hand-wheel and, at the same time, operate the contact and the cooling water valve. (In stopping the machine, the said operations will take place in the reverse order.)

In order to adjust the pressure within the receptacle 6 the following provision is made. Extending between the top of the receptacle 5 and the top of the receptacle 6 is a connection 15. Said connection is controlled by a needle valve 16 which is in turn controlled by the pressure existing in the air space of the receptacle 1 through the intermedium of a diaphragm 17 subjected to said pressure, said diaphragm being connected to the stem of said needle valve.

The operation of this regulating device is as follows:

With the pressures inside the chambers 1 and 3 at equal height the diaphragm 17 will be about its central position so as to keep the control valve 16 slightly open. Assuming the pressure in 1 exceeds that in 5, the diaphragm will be forced outwardly so as to

close the valve 16 more than before or completely. This will result in a throttling effect in the pressure conduit 8—5—15 of the small pump 7 thereby causing an increase of 5 the pressure in the receptacle 5. If the pressure in the receptacle 5 exceeds that in the chamber 1 then the diaphragm 17 will be pressed towards the chamber 1 so as to open the valve 16 thereby causing a reduction of 10 the resistance inside the pressure conduit 8—5—15 of the small pump 7, the pressure in the receptacle 5 sinking at the same time. When using a constant pressure in the chamber 1 the diaphragm and its valve may be 15 replaced by a usual safety valve in connection with the receptacle 5. In substitution for oil in the receptacles 5 and 6 any other liquid desired may be used. The pump 7 may be replaced by an air compressor, a vacuum pump, a pressure receptacle, or the like. 20

In Fig. 2 I have shown a fly-weight 12 as carried by the shaft 2 within the receptacle 5. Said weight is used as an equivalence of the hand-wheel 11 in Fig. 1, inasmuch as it may be formed with inner threads engaging corresponding threads formed in the shaft. Said fly-weight due to its inertia will be somewhat marginal in its action inasmuch as it is slow to start when the rotation of the shaft is initiated and will continue to rotate a little, after the rotation of the shaft is stopped, thereby causing a relative displacement of the shaft in the one direction or the other. In stopping the machinery the weight 12 is thus caused due to its inertia to turn on the threads of the shaft towards the hub 13 so as to abut against the end thereof and be pressed thereagainst at the same time increasing the pressure as exerted on the surface 9 by the shoulder 14 of the shaft. In starting, the inertia of the weight 12 and the sliding friction at the end of the hub 13 will cause the weight 12 to release from the end of the hub 13 thereby releasing the shaft. 45

With the interior of the receptacle 1 subjected to a vacuum the shoulder 14 of the shaft may, for instance, be designed to cooperate with the hub 13 within the receptacle

5. The hand-wheel 11 or the weight 12 may 50 in such case be modified accordingly.

What I claim is:

1. A sealing device without solid packing material for a rotating shaft projecting through the wall of a gas tight chamber, 55 comprising a closed receptacle surrounding the shaft at the point where it projects through the chamber and adapted to contain a pressure medium, means for supplying the medium to the receptacle from a source other than the chamber, automatic means for regulating the pressure of the medium in perfect conformity to the pressure existing within said chamber and a valve in connection with said shaft and adapted to be controlled by 60 the last named pressure.

2. A sealing device for a rotating shaft projecting through the wall of a gas tight chamber comprising a closed receptacle surrounding the shaft at the point where it projects through the wall and adapted to contain a pressure medium, means for supplying the medium to the receptacle from a source other than the chamber, automatic means adapted to regulate the pressure of the medium to conform with the pressure existing within the chamber, means for permitting a slight axial movement of said shaft and a valve in connection with said shaft and adapted to bear against the wall. 70

3. A sealing device for a rotating shaft that projects through the wall of a gas tight chamber, comprising a receptacle surrounding said shaft at the point where it projects through said wall and adapted to contain a 75 pressure medium, means for supplying the medium to the receptacle from a source other than the chamber, automatic means adapted to regulate the pressure of said medium to conform to the pressure existing within the 80 chamber and comprising a membrane actuated on one side by the pressure in the chamber and on the other side by the pressure in the receptacle and a regulating valve actuated by said membrane. 85

In testimony whereof I have signed my name.

RUDOLF HEINRICH WIEGERT.
